UNITED STATES PATENT OFFICE.

WILLIAM TUPPER, OF GRASS VALLEY, CALIFORNIA.

DISH-WASHING MACHINE.

1,083,380.

Specification of Letters Patent.

Patented Jan. 6, 1914.

Application filed February 23, 1912. Serial No. 679,253.

To all whom it may concern:

Be it known that I, WILLIAM TUPPER, a citizen of the United States, residing at Grass Valley, in the county of Nevada and

5 State of California, have invented new and useful Improvements in Dish-Washing Machines, of which the following is a specification.

This invention relates to dish washing 10 apparatus.

The object of the present invention is to provide a simple, substantial, easily operated machine for the washing of dishes, etc.

The invention consists of the parts and 15 the construction and combination of parts as hereinafter more fully described and claimed, having reference to the accompanying drawings, in which—

Figure 1 is a vertical transverse section 20 through the machine. Fig. 2 is a horizontal section through the machine.

In the illustrated embodiment of the invention 2 is a suitably shaped tank, shown as cylindrical in form and of suitable depth, 25 having attached to its bottom a substantial support or spider 3, the projecting ends of which may be perforated, as at 4, to receive screws or other devices 5 by which the tank may be connected to a board, table or other 30 support.

On one side of the tank 2 is formed a rectangular chamber 6 on the rear side of which is mounted a gear case 7, in which is journaled a gear shaft 8 bearing a gear 9, 35 which in turn meshes with and drives a pinion 10 mounted on a transverse shaft 11, on the outer end of which may be mounted, if desired, a pulley or driving wheel, not shown, whereby the apparatus may be operated by mechanical power.

On the end of the shaft 8 is secured a crank 9' whereby the machine may be operated manually. The shaft 11 projects into the rectangular chamber 6 and is provided 45 with a packing gland 12 to prevent the leaking of water from the tank 2 when this is being used. On the inner end of the shaft 11 is a pinion 13 meshing with an annular crown gear 14 which is attached to upright 50 arms 15 of a spider or frame 16 rotatable about a central stud 17 in the bottom of the cylinder 2. A wing screw 18 may be screwed into the bearing 17 about which the upright arms 15 may revolve.

55 Dishes to be washed are placed in position in a perforated or open screen basket 20 of

suitable depth and diameter to fit within the tank 2 and rest on the frame 16 and within the annular crown gear 14 which is revolved by the pinion 13 when the gearing 9—11 is 60 operated.

One of the peculiar and special features of the present invention is the means whereby the water and soapy substance, which may be inserted in the water, can be forced 65 with great pressure and washing effect against the dishes, this means comprising in the present instance a propeller wheel 21 which may be secured on the shaft 11 to rotate in the cylinder 6 and force the cleaning 70 water, which is fed into the tank through a suitable connection 22, at the top of the chamber 6, inwardly against the dishes in the basket; the stream of water being projected inwardly by the rotation of the propeller with its shaft 11, this shaft in turn driving the frame 16 through means of the annular gear 14. The revolutions of the basket carrying the plates contained therein 75 successively around causes the current of 80 water produced by the revolving propeller 21 to thoroughly cleanse the dishes.

After the dishes have been washed, or during the operation, the sediment and unclean water may be drawn from the tank 2, 85 through a drain connection or pipe 23 located at one side and near the bottom of the tank 2.

A lid or cover 24 is provided and fittable over the upper open end of the tank 2, so 90 as to keep the steam within the tank, to maintain the water at as high a temperature as desired during the washing operation.

The basket 20, in which the dishes may be placed, may be filled with dishes before it is 95 arranged in the tank 2, and after the dishes have been thoroughly washed by the impingement of water thrown by the propeller 21, the basket with the dishes may then be lifted out and the dishes allowed to drain 100 and rinsed with fresh water, if desired.

Having thus described my invention, what I claim and desire to secure by Letters Patent is—

1. A dish washing apparatus comprising 105 a vertical tank having a closed bottom with a step bearing, a shallow, vertical chamber at one side of and opening throughout its height into the tank, a skeleton-like carrier rotatably supported by the bearing, means 110 for preventing the carrier from moving axially of the bearing, said carrier having

an annular crown-gear at the ends of upright arms, a reticulated basket approximating the diameter of the tank for utensils capable of being fitted in and laterally supported by the arms of the annular gear and resting upon the carrier, a horizontal driving shaft mounted in the wall of the side chamber at right angles to the axis of the crown-gear, and a pinion on said shaft meshing with the crown-gear.

2. A dish washing apparatus comprising a vertical tank having a closed bottom with a step bearing, a shallow, vertical chamber at one side of and opening throughout its height into the tank, a skeleton-like carrier rotatably supported by the bearing, means for preventing the carrier from moving axially of the bearing, said carrier having an annular crown-gear at the ends of up-

right arms, a reticulated basket approximating the diameter of the tank for utensils capable of being fitted in and laterally supported by the arms of the annular gear and resting upon the carrier, a horizontal driving shaft mounted in the wall of the side chamber at right angles to the axis of the crown-gear, a pinion on said shaft meshing with the crown-gear, an inlet for clear water in the chamber, and a propeller secured on the shaft for driving the clear water across the tank.

In testimony whereof I have hereunto set my hand in the presence of two subscribing witnesses.

WILLIAM TUPPER.
